UNITED STATES PATENT OFFICE

2,455,852

UNDERWEAR SUPPORTED SUSPENDER

Josephine H. Campbell, Jackson, Mich.

Application July 21, 1944, Serial No. 545,935

2 Claims. (Cl. 2—323)

1

The present invention relates to improvements in suspenders, being particularly concerned with suspenders of the concealed type and so designed as to permit the same to be supported from the wearer's underwear or other undershirt.

One of the objects of the present invention is to provide an improved suspender of the concealed type adapted to be supported from the reinforced edge of the arm hole of the underwear.

A further object of the invention is to provide an improved suspender of the concealed type which supports the pants at a point adjacent the hips and is supported from the underwear at a point beneath the arm pit.

These and other objects and advantages residing in the combination, arrangement and construction of parts will be more fully appreciated from a consideration of the following specification and annexed claims.

In the drawing, wherein two different forms of the invention are illustrated.

Fig. 1 is an elevational view of the suspender illustrating the manner in which it is supported from the underwear and connected to the pants.

Fig. 2 is a side elevational view of the construction shown in Fig. 1 and

Fig. 3 is a slightly modified form of the attachment hook.

The improvements in suspenders according to the present invention are characterized by the simplicity of construction, comfort while being worn, and the ability to fasten and unfasten the suspender from its support without removing the vest or coat.

As shown in the drawing, the suspender 10 comprises a suitable hook portion 12 so designed as to enable the same to be engaged over the reinforced edge of the opening 14 for the arm of sleeveless underwear, or undershirts, as they are more commonly known. A short adjustable strap 16 connects the hook portion 12 with the hook portion 18, which is adapted to engage with a button 20 located at the top on the inside of the pants 22, this being the conventional method of attachment for the so-called concealed suspenders worn over the shoulder.

In Fig. 3 is shown a slightly modified form of the hook made of wire, performing the function of the hook 12 shown in Fig. 1.

It will be understood that a loop 24 in the webbing 26 holds the hook 12'. It is not necessary that the adjustable strap 16 be of elastic material. It has been found that the stretch in the underwear is adequate for giving comfort to the wearer in all positions of the body. In using my

suspender, the hook 12 is hooked over the reinforced edge 14 of the arm hole of the underwear and positions the lower end of the suspender along the top of the pants or trousers, making it possible to engage the supporting button 20 along the top of the pants through the shirt with the fastener portion 18.

Should the wearer of my improved suspender desire to remove his pants or trousers, without removing his vest or coat, the suspender may be readily detached by the wearer, especially in view of the location of the suspenders adjacent the hips.

In the form of the hook 12 of Fig. 2 the attachment portion 28 is disposed in the line of tension of the strap 16. To also dispose the

10 tension of the strap 16. It also disposes the anchor loop portion 30 in the line of tension of the strap 16, an offset portion 32 is provided. By this arrangement clearance is provided for the 20 free flared end 34 defining the throat 36 for the entrance of the reinforced edge of the arm pit of the undergarment, which when fully inserted engages in the loop 30 by virtue of the tension of the strap 16. By disposing the anchor loop 30, 25 the free flared end 34, and the attachment portion 28, all in the line of tension of the strap 16, there is no tendency for any part of the hook 12 to be urged against the sides of the body of the wearer. Also, it makes it possible to wear the 30 suspender 10 on the outside of the undergarment with the hook 12 so disposed that the throat 36 is toward the body of the wearer.

Having thus described my invention, what I desire to secure by Letters Patent and claim is:

35 1. A concealed suspender for trousers having
suspender buttons at the sides on the inside of
the waistband thereof, said suspender being
adapted to be worn on the outside of a sleeveless
undershirt to be supported from the rein-
40 forcing edge of an arm hole thereof and being
concealed beneath an outer shirt and comprising
a hook having an inwardly disposed down-
wardly projecting bill engageable over the rein-
45 forcing edge of an arm hole of the sleeveless
undershirt with the bill of the hook disposed in-
wardly, said hook having the lower portion of the
body thereof offset to be substantially in the
plane with portions of the bill of the hook and
50 having a flared throat for engagement over a con-
siderable portion of the arm hole of the under-
shirt, a button engaging loop portion engage-
able over a button of the trousers with a portion
of the outer shirt interposed over the button, and
55 a flexible strap supporting said button loop por-
tion from the hook portion and having an ad-

adjustable end on the inner side whereby said adjustable end is presented to lie against the outer side of the undershirt, thereby leaving the button loop portion entirely free and open on its outer side for engagement over a trousers button, the offset formation of the hook and the connection of the loop portion being such that the bill of the hook and the loop are presented to be disposed in substantially the same line of tension when the suspender is in use and the hook portion will be disposed adjacent to the body of the wearer without projection inwardly beyond the plane of the supporting strap and the adjusting end of the supporting strap will be presented inwardly against the undershirt to thus avoid contact of this end with the outer shirt.

2. A concealed suspender for trousers having suspender buttons in the inside of the waistband thereof and adapted to be worn on the outside of a sleeveless undershirt to be supported from the reinforcing edge of an armhole thereof and to be concealed beneath an outer shirt comprising, a hook having an inwardly disposed downwardly projecting bill engageable over the reinforcing edge of an armhole of the undershirt with the bill of the hook disposed inwardly, said hook having the outer portion of the body thereof disposed to lie against the outer side of the undershirt, a button engaging loop portion engageable over a suspender button of the trousers with a portion of the outer shirt interposed over

the button, and a flexible strap adjustably supporting said button loop portion from the hook portion and having an adjustable end on the inner side of the loop whereby said adjustable end is presented to lie against the outer side of the undershirt and thereby leave the button loop portion entirely free and open on its outer side for engagement over a trousers button with the adjusting end of the supporting strap presented inwardly against the undershirt to thus avoid contact of this end with the outer shirt.
